UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

QUICK-ACTING WARP STOP MECHANISM FOR WARPERS.

Application filed February 15, 1926. Serial No. 88,247.

This invention relates to improvements in quick-acting warp stop mechanisms for warpers having a transversely oscillating detector bar and the general object of the invention is to provide means for more quickly stopping the warper upon the falling of a drop wire than in previous constructions.

Breakage of the warp coming from the creel to the warper may occur near the beam upon which it is to be wound, or the warp may break in front of the stop motion and the trailing end be carried on to the beam. In usual constructions, where the stoppage of the warper is delayed after detection of a broken warp, many yards of warp are apt to be carried along before the warper is completely stopped, so that in piecing the ends, it is almost impossible not to cross them, for, if the ends are wound around the beam and the broken end has to be found after it has been wound upon the beam, it is almost impossible to piece up and keep the warps in line. Consequently frequently the warps are crossed. The present invention contemplates the stoppage of the warper in a small fraction of the time required for the stoppage of the ordinary warper, thereby preventing a run-over of the yarn and enabling the broken end readily to be found before it is wound upon the beam, thus avoiding a crossing of the warps.

More specifically the invention relates to improvements in warpers in which one, or more usually two, detector bars extend transversely of the warper and are rigidly secured to a detector bar shaft which is mounted in the end frames of the warper and which is provided with a downwardly extending arm which engages a device carried by a continually moving vibrator, which device is operable upon the arrest of the detector bars by a falling drop wire to initiate the action of the mechanism for stopping the warper. In usual constructions the drop wire bar is arrested by a falling drop wire in only one direction of its movement. The present invention contemplates the employment of a drop wire so constructed as to arrest the detector bar in either direction of its movement; in the usual construction the arrest of a detector bar actuates the device for initiating the action of the mechanism for stopping the warper during only one direction of movement of the vibrator. The present invention embodies mechanism for in-

itiating the action of the stop mechanism in either direction of movement of the vibrator.

The invention further contemplates the provision of a continually moving actuator having means operable at greater frequency than the frequency of movement of the vibrator to actuate the knock-off mechanism of the warper upon arrest of the detector bar, thereby still more quickly effecting the stoppage of the warper.

The invention is illustrated herein as applied to the general form of warper disclosed in my prior Patent No. 1,254,936, granted January 29, 1918. It also embodies certain features disclosed in my concurrently pending applications, Nos. 87,643 and 87,644, filed February 11, 1926.

As the present invention relates merely to the warp stop mechanism of warpers, only a sufficient portion of the warper is illustrated in the accompanying drawings to disclose the application of the invention thereto.

In the drawings:

Fig. 1 is an elevation of a portion of one of the end frames of a warper, an upper section of the same being broken away to show the detector bar and the cooperating drop wire mechanism.

Fig. 2 is a detail sectional view showing the detector bar shaft mounted in an end frame and the manner in which the detector bars are mounted thereupon.

The warper in the accompanying drawing is of the usual type comprising end frames 1 and 2 which carry the usual mechanism of the warper and upon which is mounted the detector mechanism and the means operable thereby for effecting the stoppage of the warper. A bar 3 extending transversely between the end frames of the warper is provided with a seat 4 which supports the usual series of blocks 5, in each of which a plurality of drop wires 6 are pivotally mounted and retained in separated position. A usual restoring bar 7 is carried upon arms 8 which are secured to a rock shaft 9. The bar 7 serves the double purpose of arresting the falling drop wires in substantially a horizontal position in the path of the vibrating detector and also acting, when moved upwardly by the rocking of the shaft 9, to return a fallen drop wire to normal position.

In usual constructions the ends of the drop

wires are bent upwardly and then reversely to provide an eye for the warp. In the present construction, the ends of the drop wires are bent in the reverse direction to provide an eye 10 presenting an outer shoulder 11 and an inner shoulder 12, each of which shoulders is adapted to engage and arrest the detector bar so that the detector bar would be arrested by a falling drop wire in either direction of its oscillatory movement. The oscillating detector bar 13 is in the form of a flat plate extending transversely across the warper in parallelism to the series of drop wires and desirably is provided at its upper end with laterally extending flanges 14 and 15 adapted respectively to engage the shoulders 11 and 12 of the fallen drop wire and prevent the drop wire from being raised out of engagement with the detector bar 13. The detector bar 13 is carried upon arms 16 which are fixedly secured to a detector bar shaft 17 which is journaled in suitable bearings 18 in the end frames 1 and 2 of the warper. One end of the detector bar shaft 17 is provided with a downwardly extending arm 19 which is keyed or otherwise fixedly secured thereto. The arm 19, and consequently the detector bar, is oscillated from the usual vibrator of the warper through novel controlling mechanism adapted upon the arrest of the detector bar to cause the actuation of a knock-off device for stopping the warper during either direction of movement of the vibrator.

In the preferred construction illustrated herein, the lower end of the arm 19 is provided with a cylindrical offset member 20 which frictionally engages a reentrant angle 21 on the upper face of a controller 22 which is pivotally mounted upon a stud 23 extending from the end portion of an arm 24 which extends laterally from the upper end of the vibrator 25 which is actuated by the arm 25^a of the usual rock shaft 25^b. The controller 22 is normally held in engagement with the offset member 20 of the arm 19 by a spiral spring 26 which is seated at its lower end in a socket in a boss 27 upon the elbow of the vibrator and at its upper end in a socket in a boss 28 preferably located immediately beneath the reentrant angle of the controller. By reason of this construction, the frictional engagement between the member 20 of the arm 19 of the detector bar shaft and the reentrant angle of the controller 22, the oscillating movement of the vibrator will normally be imparted to the detector shaft and the detector bars which are carried thereby. Upon arrest of the detector bar, the arm 19 will be held from movement, and as the vibrator continues its movement, the member 20 will be caused to ride up upon one of the faces of the reentrant angle, thereby depressing the controller 22 against the action of its spring 26. This yielding move-

ment of the controller is employed to initiate the action of the mechanism for stopping the warper and it will be obvious that as this yielding movement occurs upon arrest of the detector bar during either direction of movement of the vibrator, a much quicker actuation of the stopping mechanism will be obtained than in previous constructions and such action will be doubly speeded up by reason of the fact that the detector bar is arrested by a falling drop wire in either direction of its movement, so that in the mechanism thus described, the actuation of the stop mechanism is accomplished in one-quarter of the time required in usual warp stop constructions.

The present invention, however, further contemplates the provision of means for still more quickly stopping the warper. This is accomplished by providing a continually moving actuator having means operable at a greater speed than the speed of movement of the vibrator to engage a knock-off device which is normally supported by the controller out of engagement with the actuator, but is caused to engage the actuator by the yielding movement of the controller when caused by the arrest of the vibrating detector bar, as above described.

A preferred form of mechanism for accomplishing this purpose which is illustrated herein comprises a knock-off device in the form of a lever 29 which is pivotally mounted at its upper end upon a stud 30 at one end of an arm 31 which is pivotally mounted upon a stud 32 upon a bracket 33 secured to the end frame. Lugs 34 and 35 projecting from the bracket 33 limit the upward and downward movement of the arm 31, and consequently limit the movement of the knock-off device. The lower end of the lever 29 is provided with an offset portion 36 which presents a shoulder resting upon an arcuate extension 37 of the controller 22. The offset portion 36 of the lever 29 is provided with a laterally extending stud 38 which is connected by a link 39 to the usual knock-off lever 40 which knocks off the shipper 41. The lower end of the offset portion 36 of the lever 29 is provided with a vertical shoulder 42 which is adapted to be engaged by a member of a moving actuator which operates at a greater speed than the speed of movement of the vibrator. Preferably a rotating actuator is employed having one or more arms to engage the shoulder 42 of the knock-off device and having such speed of rotation as may be required to provide a very quick actuation thereof.

In the preferred embodiment of the invention, the actuator comprises a star wheel 43 fixedly secured upon a continuously rotating shaft 44 and having a series of arms 45, any one of which may engage the shoulder 42 of the knock-off device when the latter is 133

depressed into the path thereof, thereby effecting almost instantaneous actuation of the knock-off device or lever 29 and consequent immediate actuation of the knock-off lever. 5 In the operation of the warp stopping mechanism above described, a falling drop wire will engage the detector bar 13 in either direction of its movement, thereby arresting the arm 19 of the detector bar shaft. The 10 arrest of the arm 19 during the movement of the vibrator 25 in either direction will cause immediate depression of the controller 22 against the action of its spring 26, thereby permitting or causing the detector device or lever 29 to be depressed so that its shoulder 42 will be engaged by one of the arms 45 of the rotating actuator, so that the lever 29 will be swung upon its pivot 30 and the rod 39 caused to rock the knock-off lever 40, thereby releasing the shipper and causing immediate stoppage of the warper.

By thus stopping the warper in a relatively small fraction of the time required for the stoppage of the usual warper, there is 25 much less run-over of the yarn and crossing of the warps. Furthermore, the prompt stoppage of the warper enables the broken end to be more readily found for piecing.

Having thus described the invention, what 30 is claimed as new, and desired to be secured by Letters Patent, is:

1. Quick-acting warp stop mechanism for warpers comprising a detector bar; means for oscillating the same transversely of its 35 length, a series of pivotally mounted drop wires operable when permitted to fall to arrest the detector bar, in either direction of its movement, a continually moving vibrator, a yieldable controller mounted on said vibrator, means engaging said controller normally acting to transmit an oscillating movement therefrom to the detector bar, and operable upon arrest of said detector bar to cause said controller to yield during the 40 movement of said vibrator in either direction and means operable by the yielding movement of said controller immediately to effect a stoppage of the warper.

2. Quick-acting warp stop mechanism for warpers comprising a detector bar, means for oscillating the same transversely of its 45 length, a series of pivotally mounted drop wires operable when permitted to fall to arrest said detector bar, a continually moving vibrator, a knock-off device, an actuator therefor having means operable at a greater speed than the speed of movement of said vibrator to actuate said knock-off device when engaged thereby and a yieldable controller mounted on said vibrator normally supporting said knock-off device out of engagement with said actuator and also acting to transmit an oscillatory movement to said detector bar from said vibrator and operable 55 upon arrest of the detector bar by a falling

drop wire to cause said knock-off device to engage said actuator and thereby effect a prompt stoppage of the warper.

3. Quick-acting warp stop mechanism for warpers comprising a transverse detector bar shaft having a detector bar fixedly secured thereto, a series of pivotally mounted drop wires each having means operable upon the falling of the drop wire to engage and arrest said detector bar in either direction of its movement, a continually moving vibrator, a yielding controller mounted thereon, relatively movable interengaging means connecting said controller to said detector bar shaft acting normally to transmit an oscillatory movement to said detector bar from said vibrator, but operable upon arrest of the detector bar to cause said controller to yield during the movement of the vibrator in either direction and means operable by such yielding movement immediately to effect a stoppage of the warper.

4. Quick-acting warp stop mechanism for warpers comprising a transverse detector bar shaft having a detector bar fixedly secured thereto, a series of pivotally mounted drop wires each having means operable upon the falling of the drop wire to engage and arrest said detector bar in either direction of its movement, a continually moving vibrator, a yielding controller mounted thereon having faces presenting a re-entrant angle, an arm fixedly secured to said detector bar shaft having means frictionally engaging said re-entrant angle and operable upon arrest of the detector bar by a falling drop wire to ride up upon one of the walls of said re-entrant angle and thereby cause said controller to yield during either direction of movement of said vibrator and means operable by such yielding movement immediately to effect a stoppage of the warper.

5. Quick-acting warp stop mechanism for warpers comprising a transverse detector bar shaft having a detector bar fixedly secured thereto, a series of pivotally mounted drop wires each having means operable upon the falling of the drop wire to engage and arrest said detector bar in either direction of its movement, a continually moving vibrator, a knock-off device, an actuator therefor having means operable at a greater speed than the speed of movement of said vibrator to actuate said knock-off device when engaged thereby, a yielding controller carried by said vibrator normally supporting said knock-off device out of engagement with said actuator and having a face presenting a re-entrant angle, an arm fixedly secured to said detector bar shaft having means frictionally engaging said re-entrant angle and operable upon arrest of said detector bar to depress said controller in either direction of movement of said vibrator whereby said knock-off device is caused to

engage said actuator and a quick stoppage of the warper effected.

6. Quick-acting warp stop mechanism for warpers comprising a transverse detector bar shaft having a detector bar rigidly secured thereto, a series of pivotally mounted drop wires each having means operable upon the falling of the drop wire to engage and arrest said detector bar in either direction of its movement, a continually moving vibrator, a knock-off device, a continuously rotating actuator having means operable at a greater speed than the speed of movement of said vibrator to actuate said knock-off device when engaged thereby, a yielding controller carried by said vibrator normally supporting said knock-off device out of engagement with said actuator and having a face presenting a re-entrant angle, an arm fixedly secured to said detector bar having means to engage said re-entrant angle and operable upon the arrest of said detector bar to depress said controller and thereby cause said knock-off to engage said actuator, whereby prompt stoppage of the warper will be effected.

7. Quick-acting warp stop mechanism for warpers comprising an oscillating detector bar shaft having a detector bar rigidly connected thereto and a depending arm, a series of drop wires co-operating with the detector bar having means operable upon the falling of a drop wire to engage and arrest the detector bar during either direction of its movement, a continually moving vibrator, a downwardly yieldable controller carried by said vibrator having a face presenting a re-entrant angle frictionally engaging the depending arm on said detector bar shaft and adapted to be depressed thereby upon arrest of the detector bar, a knock-off device normally supported by said controller, a continually rotating star wheel located beneath said knock-off device and rotating at such speed that the knock-off device will be engaged by one of the arms of the star wheel immediately upon the depression of the controller, whereby prompt stoppage of the warper will be effected.

In testimony whereof, I have signed my name to this specification.

ALONZO E. RHOADES.
